EARTH ANCHOR DEVICE.

Application filed January 14, 1924. Serial No. 686,070.

The object of our invention is to provide an earth anchor device of simple, durable and inexpensive construction, especially designed for use in supporting guy wires for posts or the like.

More specifically it is our object to provide an anchor device which may be inserted in the earth in a hole of relatively small diameter, and in which the anchor blades may then be positively and uniformly forced outwardly into the earth surrounding the opening, to thereby grip a relative area of earth surrounding the opening; and

Further in this connection it is our object to provide a means for expanding the anchor blades whereby they may be expanded in a convenient and facile manner.

A further object is to provide a device of this character in which the anchor head and blades may be formed of cast metal and readily and quickly assembled in position for operation without any machine work, whereby the cost of construction is minimized.

A further object is to provide an anchor device of this character in which the part of the anchor device which serves to expand the anchor blades in the earth may be readily, quickly and easily detached from the parts that remain permanently in the ground, so that only one expanding member need be used in connection with an unlimited number of the anchor parts that remain permanently in the ground.

Our invention consists in the construction, arrangement and combination of the various parts of the device, whereby the objects contemplated are attained, as hereinafter more fully set forth, pointed out in our claim, and illustrated in the accompanying drawings in which:

Figure 1 shows a side elevation partly in section illustrating our complete anchor device inserted in an opening in the ground with the anchor blades in their folded position.

Figure 2 shows a similar view of the lower portion of the anchor device with the anchor blades expanded.

Figure 3 shows a top or plan view illustrating the expanding device.

Figure 4 shows a top or plan view of the anchor head with two of the blades in folded

positions, and two of the blades in expanded position; and

55

Figure 5 shows an enlarged detail sectional view illustrating a part of the anchor head and one of the anchor blades, the latter being shown in solid lines in position for being connected to the head, and the dotted lines show its position after it is connected to the head and in an expanded position.

60

Figure 6 shows a side elevation of a modified form of our invention partly in section. The dotted lines show the position that the anchor blades will assume when expanded.

65

Figure 7 shows a top or plan view of the same.

70

Figure 8 shows a sectional view on the line 8—8 of Figure 6.

Referring to the accompanying drawings, we have used the reference numeral 10 to indicate the body portion of the anchor head. This is substantially rectangular in outline and is provided with a central longitudinal opening at 11 and a nut recess 12 at its bottom, the opening being designed to receive the anchor rod 13 upon which the nut 14 is mounted to rest in said recess 12.

75

At each side of the body portion there is formed a curved slot 15 with a bearing pin 16 at the upper outer portion of the slot, as shown in Figure 5. There are preferably four anchor blades, each of which comprises a body portion 16^a having at one end a curved hook 17 and adjacent to the hook a shoulder 18. The body is preferably curved in the manner clearly illustrated in Figure 2.

80

Two oppositely disposed ones of the blades 16 and their side edges formed with outwardly extended curves as at 17 in Figure 4, and the opposite ones have their side edges curved inwardly at as 18 in Figure 4, so that when two adjacent blades are arranged in folded position, as shown at the upper right side of Figure 4, the outwardly curved portion of one blade will fit into the inwardly curved portion of the adjacent blade, and thus permit the blades to occupy a minimum space and fit close together around the supporting rod 13.

95

These parts are so arranged and proportioned that when the upper ends of the blades are tilted to position overlapping the center of the body portion 10, as shown

100

105

in solid lines in Figure 5, the hook 17 may freely enter the slots 15, and engage the bearing pins 16. Then the blades may be folded up to position adjacent to the rod 13, as shown in Figure 1. When, however, the blades are tilted outwardly in their expanded position, the shoulder 18 thereof will engage the outer surface of the body 10, as shown by dotted lines in Figure 5, thus limiting the further outward movement of the blades.

For the purpose of expanding the blades into the earth we provide an expander tube 19 having fixed to its lower end an expander head 20, which head is preferably octagonal in shape at its outer edges and is of such size that when the head is placed adjacent to the upper ends of the anchor blades when they are in their folded position, the head will enter between the upper edges of said blades, and one of the flat sides of the head engaging each of the blades, as shown in Figure 1.

Fitted into the upper end of the expander tube 17 is a bearing block 21 having a central opening through it, through which is extended a screw threaded rod 22 having a hook 23 at its lower end designed to engage the upper end of the rod 13, as shown in Figure 1. Mounted upon the top of the rod 22 above the bearing block 21 is a nut 24 having handles 25 thereon for turning it.

In practical operation the anchor device is assembled as follows:

Before the insertion of the rod 13, the blades are hooked into position, as before described, then the rod is inserted between the blades and through the opening 11 and the nut 14 placed on the bottom. This rod prevents the blades from moving inwardly far enough to unhook from the anchor body 10, so that these parts are permanently assembled. Then the operator forms a hole in the earth at the desired position. It is only necessary to make this hole approximately the same diameter as the blades when in their folded position. Then the screw threaded rod 22 is hooked to the rod 13 above the ground and the tube or pipe 19 with its expander head 20 is slid over these rods 13 and 22. Then the bearing block 21 is placed in position inside of the upper end of the tube 19 and surrounding the screw threaded rod 22, and then the nut 24 is screwed on the upper end of the rod 22. Then the operator manipulates the nut 24 by the handles 25. This causes the expander head 20 to engage the upper inner ends of the anchor blades. As the screw pressure is increased, there will be a downward pressure by the expander head on the blades and an upper pressure on the blade against the expander head, substantially equalized, and the result of which is that the tops of the blades are first forced out-

wardly into engagement with the earth. Then the blades move upwardly and outwardly following the line of their curvature until they are fully expanded, as shown in Figure 2, whereupon further outward movement is prevented by the engagement of the shoulder 18 against the body 10.

When this has been done, the nut 24 is removed and the rod 22 is unhooked from the rod 13. Then the tube with the expander head is removed from the opening in the ground and the anchor is ready for use.

Obviously by our improved method of expanding the anchor blades, a relatively small sized opening may be made in the ground and a maximum expansion given to the anchor when opened out.

Furthermore, the parts which remain in the ground are of simple, durable and inexpensive construction and do not need any machining, and may be readily, quickly and easily assembled.

In the modified form of our invention, illustrated in Figures 6, 7 and 8, the lower end of the rod 13 is screw threaded up to a point above the tops of the anchor blades when in their folded position, and the nut 26 is mounted on said rod from its lower end and screwed up to a point above the top of the anchor blades when folded. Then an expanding blade 27 is placed on the rod from below and its upper end engages the nut 26 to limit its upper movement relative to the rod, and said blade is freely rotatable on the rod 13. This blade is provided with curved notches 28 on its four sides designed to receive and engage the upper inner faces of the anchor blade when folded. The body portion 10, the nut 14 and the anchor blades 17 and 18 are the same as in the other form of our invention.

In this form of the invention we have also provided a means for preventing the hooks at the lower ends of the anchor blades 17 and 18 from frictionally engaging the adjacent surfaces of the body 10 when pressure is applied in a downward direction to the upper ends of the anchor members by the member 27. This we accomplish by forming a rib 30 on the blade 18 above the point where the blade engages the pin 16 so that all of the downward thrust is carried by the rib 30 engaging the smooth rounded surface of the pin and none of it is transmitted to the relatively rough and uneven contacting surface between the under surface of the hook and the adjacent curved surface of the body portion 10.

After the anchor members have been expanded and a pull is applied to the rod 13 and the ends of the anchor blades are embedded in the ground, then considerable pressure is applied to the hooks on the ends of the anchor blades in an upward direc-

tion against the pin 16, and for the purpose of preventing this pressure from reaching the point of breaking strains as applied to the hook, we have beveled the lower corners 5 of the body portion 10 downwardly and toward a vertical line at 31 through the center of the body portion, and we have also correspondingly beveled the shoulders 18^a and the lower ends of the anchor blades so 10 that when the shoulder 18^a contacts with these beveled portions 31, they will prevent an upward thrust by the hooks against the pin 16, to thereby relieve any possibility of breaking strain as applied to these hooks 15 and throw all of the strains on the reinforced portions of the anchor blades.

In practical use of this modified form the parts are adjusted to position so that the upper inner edges of the anchor blades 20 engage their respective notches in the periphery of the spreader plate. Then the anchor is inserted in a hole formed in the ground for this purpose, and the rod 13 is inserted in the ground to the desired distance. Then the rod 13 is turned which has the effect of moving the body 10 upwardly in the hole and toward the spreader plate. When this turning movement is first 25 commenced some or all of the outer ends of the anchor blades will be embedded in the walls of the hole, and this will prevent the rotation of any of the parts of the device, except the rod itself. As the turning of the rod continues, the blades will be 30 forced upwardly and outwardly to the position shown by dotted lines in Figure 6, and when this has been done, the blades will

be firmly anchored in the ground surrounding the hole.

We claim as our invention:

In an earth anchor device, the combination of an anchor rod having its lower end screw threaded, a body fixed to the lower end of the rod and formed with a series of slots at its upper corners, a bearing pin 45 extended through each slot and seated in said body portion, the body portion below the slot being formed with a shoulder, a series of blades each being formed near its lower end with a hook designed to enter the 50 lower portion of one of the slots and to extend upwardly and inwardly around the bearing pin in said slot, and each being also formed at its lower end with a downwardly 55 extended lug designed to engage said shoulder when the upper end of the blade has been moved to its outward limit, whereby the blades may be readily, quickly and easily detached from the body when their upper ends are at their inner limit of movement but 60 are held against removal when the blades are at any other angle relative to the rod, and whereby when the blades are fully extended 65 they will be locked against further outward movement by said bearing pins and shoulders, and a spreader plate rotatively mounted upon the rod but held against downward movement thereon, said spreader plate being designed to engage said blades and cause them to move outwardly when said body 70 portion is moved upwardly relative to the spreader plate.
